CLAIM

The ornamental design for an automobile wheel as shown and described.

DESCRIPTION

FIG. 1 is a perspective view of an automobile wheel in accordance with our new design;

FIG. 2 is a front elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The rear view of the automobile wheel forms no part of the claimed design. The broken lines and the half-tone gray area within the broken lines shown in FIGS. 1-6 represent the environmental structure and form no part of the claimed design.
